UNITED STATES PATENT OFFICE

2,446,155

HOLDER FOR SURGICAL ACCESSORIES

John D. Karle, Roselle Park, N. J., assignor to
The Singer Manufacturing Company, Elizabeth, N. J., a corporation of New Jersey

Original application July 4, 1942, Serial No. 449,824. Divided and this application July 13, 1944, Serial No. 544,786

8 Claims. (Cl. 206—16)

1

This application is a division of my pending United States patent application Serial No. 449,824 filed July 4, 1942, which has matured into Patent No. 2,399,040, dated April 23, 1946.

This invention relates to holders for surgical accessories and it has as an object to provide improved means, designed particularly for use in conjunction with a portable container for a surgical stitching instrument, for holding the various accessories used with the instrument, such, for example, as needles, spools etc.

Another object of the invention is to provide improved holding means for the various accessories used with a surgical stitching instrument, which means is particularly adapted to be carried in a portable sterilizing container for the instrument in such a manner that they will constantly be subjected to the action of sterilizing fluid within the container.

Still another object is to provide improved holding means for surgical accessories which permits the accessories to be sterilized, while in the container, by an autoclave or other sterilizing equipment commonly available in hospitals and the like, and which permits removal and use of selected ones of the accessories without contamination of the others.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings,

Fig. 1 is a side elevation of a holder for surgical stitching instruments and their accessories, adapted for office and hospital use.

Fig. 2 is a longitudinal sectional view of the holder, showing a surgical stitching instrument and its accessories supported therein.

Fig. 3 is a top end view of the holder with the closure cap removed, showing the instrument and its accessories nested therein.

Fig. 4 is an inside view of the closure cap.

Fig. 5 is an elevation, partly in section, of the upper end of the holder, showing the closure cap partially removed therefrom, for a purpose later to be described.

Fig. 6 is a side elevation of an accessory-carrying member adapted to be supported in the holder, showing a plurality of spools and a spool-winder mounted thereon.

2

Fig. 7 is a side elevation of a second accessory carrying member adapted to be supported in the holder, showing a plurality of suturing needles carried thereby.

Fig. 8 is a transverse section of the needle-carrying member, taken on the line 8—8 of Fig. 7.

Fig. 9 is a side elevation of my improved holder for surgical stitching instruments and their accessories, when fitted for field use, showing a ground-penetrating support therefor in retracted position.

Fig. 10 is a view of the lower portion of the holder shown in Fig. 9 with the ground-penetrating support rotated thereon and extended for insertion into the ground.

Fig. 11 is a bottom end view of the device as shown in Fig. 10 with a certain belt-attaching clamp omitted.

Fig. 12 is a side elevation of a modified form of needle-holder adapted to be supported in the container.

Fig. 13 is a longitudinal sectional view on the line 13—13 of Fig. 12.

Referring more specifically to the drawings and first to Figs. 1 to 8 inclusive, the invention is disclosed as embodied in a device comprising a can-like container 1 having its lower end closed and its upper end open and exteriorly threaded, as at 2. A closure cap 3 is internally threaded, as at 4, to screw upon the threaded upper end of the container. To prevent loss of the cap, it may be attached to the container, as, for example, by a chain 5, attached to the container by a screw 6 and to the cap by a swivel connection 7 which permits free rotation of the cap. The cap 3 is with an internal hub 8 circumferentially grooved to receive and hold the small end of a bee-hive spring 9 to the larger end of which is attached a disk 10 adapted, when the cap is screwed down upon the container, as shown in Fig. 2, to act as a pressure plate to hold the suturing instrument and the accessory holders therein against displacement.

To effect a tight seal between the container 1 and the cap 3, the container is formed, below the threads 2, with an annular substantially frustoconical shoulder 11 adapted to be engaged by the frusto-conical inner face 12 of the skirt portion of the cap. As shown most clearly in Fig. 5, the upper surface of the shoulder 11 is slightly rounded in cross-section so that a line contact is obtained between the shoulder and the cap when the cap is screwed down.

Secured in chord-like position in the open upper end of the container 1 are a pair of acces-

sory-holder supporting bars 13 and 14 adapted to receive and support the hooked upper ends 15^a and 16^a of accessory-carrying members 15 and 16, respectively. A suturing instrument S is arranged lengthwise within the container 1 between the accessory-carrying members 15 and 16. The suturing instrument may be that disclosed in my United States Patent No. 2,348,218, May 9, 1944.

The member 15 comprises a strip of flat metal carrying a plurality of split studs 17 adapted to support and frictionally retain suture-carrying spools 18 designed for use in the surgical stitching instrument S. At its lower end, the member 15 is formed with a split tube 19 adapted to receive and frictionally retain a spool-winder 20 adapted to hold and wind suturing thread on the spools 18. Intermediate the spools 18 and the spool-winder, the member 15 carries a plurality of outwardly projecting pins 21 arranged to receive and hold a bent sheet metal arm 22^x carrying a thread-guide and tension for the thread to be wound on the spools 18. This spool-winder, and a similar thread-guide, together with the means employed for attaching them to the handle of the suturing instrument when it is desired to wind suturing thread on the spools, are disclosed in my United States Patent No. 2,328,557, Sept. 7, 1943.

The accessory holder 16 is designed to hold curved needles for use in the surgical stitching instrument S and comprises a sheet metal blank folded as illustrated in Fig. 8 to provide needle-shank-clamping side walls 16^b between which the shanks 22^a of needles 22 are adapted to be frictionally held. The points of the needles also may be located between the side walls 16^b to protect the points and to prevent a user from accidentally coming into contact therewith.

The container disclosed in Figs. 1 to 5 is designed primarily for office and hospital use where conventional sterilizing equipment is available. For that reason, the neck portion 23 of the container 1, i. e. the portion between the shoulder 11 and the threads 2, is formed with a plurality of slots or apertures 24 which (when the cap 3 is partially unscrewed and the container, with the instrument and accessories therein, is placed in an autoclave or other suitable sterilizing unit) permit the sterilizing fluid to enter the container, as indicated by the arrows x in Fig. 5, to sterilize the inside of the container and everything therein. Sterilization having been completed the cap is screwed down upon the shoulder 11 and the parts are maintained in sterile condition.

The construction disclosed in Figs. 1 to 5 may also be used to advantage by general practitioners for emergency suturing. For this purpose the container may be substantially filled with a sterilizing liquid into which the surgical stitching instrument and its accessories may be immersed and maintained in sterile condition for instant use.

In Figs. 12 and 13 there is disclosed a modified form of needle-holder also adapted to be supported by the cross-bar 14 in the mouth of the container 1. This modified needle-holder comprises a sheet metal strip 25 having, at one end, a hook-portion 26, designed to hang upon the cross-bar 14, and a finger piece 27 designed to facilitate withdrawing of the holder from the container. Secured to the strip 25, at spaced intervals, by rivets 28 are spring-clips 29 adapted frictionally to engage the shanks s of needles n laid upon the strip 25 and abutting a flange 30 formed on one edge of the strip. Preferably the strip 25 is aper-

tured beneath the free end of each clip 29, as indicated at 50, to render the clips more effective in holding the needles. The upper end of each spring clip 29 is preferably flared outwardly at 31 to form a finger-piece by means of which the clip may be flexed to facilitate insertion and removal of the needles. If desired the needles may be inserted behind the clips 29 by merely placing the shank thereof against the strip 25 above a clip 29 and then moving the needle downwardly against and beyond the finger piece 31. This movement of the needle shank will flex the clip and admit the shank of the needle into the semi-cylindrical socket 32 provided by the clip.

For field use, the holder may be modified as illustrated in Figs. 9, 10 and 11. This modified construction differs from the construction hereinbefore described in that the container 1 is provided with a bayonet-like ground-penetrating support 33 curved in cross-section so as to fit the outside of the container 1, as shown in Fig. 11, and designed to have its pointed end forced into the ground to hold the container in upright position while the suturing instrument is being used. The support 33 is fixed to a sleeve 34 rotatably and slidably fitted upon the outside of the container 1 and adapted to be slid upwardly thereon, to the retracted position shown in Fig. 9, when not in use, or to be slid downwardly thereon, to the position shown in Fig. 10, when it is desired to insert the support into the ground. When the support is retracted the sleeve 34 is partially rotated on the container 1 to bring the pointed end 35 of the member 33 into contact with the upper side of one of the two projecting ends 36^a of a plate 36 which is fitted into a recess 36^b in the bottom wall of the container and held therein by screws 37. This holds the member 33 in retracted position. At its lower end, the sleeve 34 is formed with two diametrically opposite outwardly expanded flat loops 38 which afford clearance for the projecting ends 36^a of the plate 36 and, at the upper end of said loops, with two circumferentially disposed slots 39 into which the ends 36^a are adapted to be rotated. The ends 36^a, the loops 38 and the slots 39 constitute a form of bayonet joint for maintaining the sleeve 34 and the member 33 in their projected or operative positions. A spring clamp 40, attached to a wire loop 41, connected to the member 33, serves as means to support the holder on the belt of a surgeon for the purpose of transportation.

For field service the container 1 is preferably filled with a suitable sterilizing fluid into which the instrument S and the accessories may be immersed after each use. Supporting of the container 1 in upright position, as by inserting the member 33 into the ground, prevents spilling of the sterilizing fluid while the instrument is in use.

When fitted for office and hospital use, as shown in Figs. 1 and 2, the recess 36^b in the bottom wall of the container may be filled with a dummy plate 42, which is shorter than the plate 36 and whose ends are flush with the side wall of the container.

From the foregoing it will be perceived that this invention has provided improved means for holding surgical accessories in a portable sterilizing container for a surgical stitching instrument, which means is simple in construction, inexpensive to manufacture, efficient in operation and which will effectively prevent disarrangement and loss of the accessories, especially when the container and surgical stitching instrument with

which they are associated are used in the field and under extremely adverse conditions.

Having thus set forth the nature of the invention, what I claim herein is:

1. An accessory holder for use in a can-like sterilizing container for a surgical stitching instrument having a supporting bar arranged across its open end, comprising a strip of metal having a hooked end designed to be hung on said bar and friction means for securing needles to said strip.

2. An accessory holder for use in a can-like sterilizing container for a surgical stitching instrument having a supporting bar arranged across its open end, comprising a folded strip of sheet metal having a hooked end designed to be hung on said bar and having its opposed walls spaced apart for frictionally holding therebetween the shanks of a plurality of needles for use in said instrument.

3. An accessory holder for use in a can-like sterilizer container for a surgical stitching instrument having a supporting bar arranged across its open end; comprising a strip of metal having a hooked end designed to be hung on said bar, and a plurality of spring clips secured to said metal strip for frictionally gripping the shanks of surgical needles placed against the side of said strip.

4. An accessory holder for use in a can-like sterilizing container for a surgical stitching instrument having an accessory-holder positioning member within the container, comprising a relatively long and narrow strip of sheet material designed to be retained lengthwise within said container by the accessory-holder positioning member and friction means for securing needles to said strip.

5. In combination with a can-like sterilizing container for a surgical stitching instrument having a supporting bar arranged across its open end, an accessory holder comprising a relatively long and narrow metallic member formed with a hooked end engaging said supporting bar to maintain said member suspended in said container, and means frictionally to support on said member accessories for a surgical stitching instrument.

6. In combination with a can-like sterilizing container for a surgical stitching instrument having a pair of supporting-bars arranged in chord-like position across its open end, a pair of accessory holders each comprising a strip of metal having a hooked end adapted to be hung on one

of said supporting bars in substantial parallelism with each other, a plurality of split spool-supporting studs projecting laterally from one of said accessory holders, means on said one of said holders for frictionally securing thereon a thread-guiding device and a spool-winding device, and means for frictionally securing to the other accessory holder a plurality of surgical needles.

10 7. An accessory holder for use in a can-like sterilizing container for a surgical stitching instrument, comprising a relatively long and narrow sheet metal member having at its upper end a flat hook portion designed to engage a part of the container and to be removably suspended lengthwise therein, and friction means provided by said member yieldingly to support accessories for a surgical stitching instrument.

15 8. The combination with a can-like sterilizing container for a surgical stitching instrument having a cylindrical casing and an accessory holder positioning member secured in its upper end and extending chord-like thereacross, of an accessory holder comprising a strip of sheet metal having a hook-shaped upper end engaging said member to support the holder in vertical position in said container, said accessory holder being provided at one side with a plurality of transversely disposed spool-supporting studs and a plurality of spaced pins adapted to engage and support a thread-guiding member, said accessory holder also being provided with an axially arranged split-tube for frictionally holding a spool-winding device.
